UNITED STATES PATENT OFFICE.

JOHN F. GRACE, OF KEARNY, NEW JERSEY, ASSIGNEE TO WORTHINGTON PUMP & MACHINERY CORPORATION, A CORPORATION OF VIRGINIA.

SURFACE CONDENSER.

Application filed March 24, 1923. Serial No. 627,266.

This invention relates to improvements in surface condensers and especially to the flow of circulation or cooling water therethrough.

- 5 The especial object of this invention is to provide a surface condenser which is especially adapted for use of a long condenser shell and large quantities of cooling water without building up undesirable friction.
 10 A further object of the invention is to obtain an equalized steam distribution through the condenser whereby approximately equal quantities of steam will be condensed in each end of the condenser and 15 the air and uncondensed vapors are evenly cooled.

The invention is illustrated in its preferred form in the accompanying drawing forming a part of this specification, and this 20 construction will now be described in detail and the features forming the invention then specifically pointed out in the claims.

In the drawing—

Fig. 1 is a vertical section of a surface 25 condenser according to my invention;

Fig. 2 is a side elevation of another form of the invention; and,

Fig. 3 is a sectional plan thereof, the section being on line 3—3 of Fig. 2.

30 Referring to the drawing, and for the moment to Fig. 1 thereof: The surface condenser comprises a shell 10 enclosing a steam space 11 traversed from end to end by cooling tubes 12, the ends of which are secured in the usual manner in tube plates 13 enclosed by water boxes or heads 14 and 15. As is usual the shell 10 includes an inlet 16 for the steam and a hot well 17 for the water of condensation which is withdrawn 35 therefrom through pipe 18.

The cooling or circulation water is supplied to the tubes 12 for condensation of the steam in space 11 by a pump 19 through connection 20 which is preferably divided 40 into two branches 21 and 22. Branch connection 21 discharges into water box or head 15 which is divided horizontally by a diaphragm 1 to form, preferably, a water inlet chamber *a* to which branch connection 45 21 is connected and a discharge chamber *b* provided with a discharge connection 23. The other branch connection 22 connects preferably with the upper end of the water box or head 14 which is divided by diaphragm 50 2 into a return flow chamber *c* and a water

inlet chamber *d* into which the branch connection 22 discharges.

The operation of this construction is as follows—

A portion of the circulation water delivered by pump 19 passes through branch connection 21 to water inlet chamber *a* in water box 15, from which it passes through the tubes 12 located below the diaphragm 1 to the return flow chamber *c* of water box 14. This flow is now directed by diaphragm 2 into those tubes located in planes between the two diaphragms for return flow to discharge chamber *b* from which it is withdrawn through discharge connection 23. The other portion of the circulation water passes through branch connection 22 to water inlet chamber *d* in water box 14 and is directed by diaphragm 2 through the upper tubes of the condenser to discharge chamber *b* in water box 15 for withdrawal through discharge connection 23.

From the above it will be seen that the flow of the circulation water through the condenser is divided into a single-pass flow through the upper tubes thereof and into a two-pass flow through the lower tubes for reduction of friction and to prevent the discharge of any unheated water.

Furthermore, an approximately equal condensation of steam is secured in each end of the condenser by directing the flow through the single-pass and the first stage of the two-pass portions in opposite directions. As an aid in accomplishing this result the steam space 11 may be divided by a vertical partition 3 if desired.

Figures 2 and 3 show a further development of this idea as applied in a single-pass condenser. In this construction the water boxes 14 and 15 are divided by vertical diaphragms, respectively 4 and 5, into water inlet chambers *e* and *f* and discharge chambers *g* and *h*, having respectively discharge connections 6 and 7. The chambers *e* and *h* are oppositely located and connected by a portion of the tubes 12 and the chambers *f* and *g* are similarly located and connected by the rest of the tubes. The circulation water supply pipe is formed with two branch connections 8 and 9 which connect respectively with the chambers *e* and *f*. With this construction the diaphragm 3 in the steam space 11 is also used.

In operation the circulation water passes

through branch connections 8 and 9 to the water supply chambers *e* and *f*, at opposite ends of the condenser, and then in two single pass opposite flows through the tubes 12 to the discharge chambers *g* and *h* from which the water is withdrawn through discharge connections 6 and 7.

It will be understood that the invention is not to be limited to the specific structure shown and described as many modifications may be made therein within the invention defined by the claims.

What I claim is:

1. A surface condenser comprising a steam space traversed by cooling tubes, water boxes at the tube ends, and means dividing the cooling tubes into an upper single-pass group and a lower two-pass group, the cooling water passing through the single-pass group 20 and the first stage of the two-pass group in opposite directions.

2. A surface condenser comprising a steam space traversed by cooling tubes, water boxes at the tube ends, and means dividing the 25 cooling tubes into an upper single-pass group and a lower two-pass group, the first stage of the two-pass group being located below the second stage thereof and the cooling water passing through the single-pass group 30 and the first stage of the two-pass group in opposite directions.

3. A surface condenser comprising a steam space traversed by cooling tubes, water boxes at the tube ends, partitions dividing each of the water boxes into two chambers, a circulating water pump, and connections between the pump and the lower chamber of one water box and the upper chamber of the other water box.

4. A surface condenser comprising a steam space traversed by cooling tubes, water boxes at the tube ends, partition means in the water boxes dividing the tubes into two groups, a circulating water inlet for each group located at opposite ends of the condenser, means for supplying circulating water at substantially the same temperature and pressure to each of said inlets, and a vertical partition dividing the steam space 45 equally.

5. A surface condenser comprising a steam space traversed by cooling tubes, water boxes at the tube ends, partition means in the water boxes dividing the tubes into two groups, a circulating water inlet for each group located at opposite ends of the condenser, and means for supplying circulating water at substantially the same temperature and pressure to each of said inlets. 50

6. A surface condenser comprising a steam space traversed by cooling tubes, water boxes at the tube ends, partitions dividing each of the water boxes into two chambers, a circulating water pump, connections between the pump and the lower chamber of one water box and the upper chamber of the other water box, and a vertical partition dividing the steam space 60 equally.

7. A surface condenser, comprising a casing, water tubes extending into the casing transverse to the line of steam flow therethrough, and means for supplying water to substantially equal numbers of said tubes at substantially the same temperature and in opposite directions of flow. 70

In testimony whereof, I have hereunto set my hand.

JOHN F. GRACE.
